UNITED STATES PATENT OFFICE.

EDWARD A. SANDERS, OF OAKLAND, CALIFORNIA.

SHEET-METAL WINDOW CONSTRUCTION.

No. 888,657.

Specification of Letters Patent.

Patented May 26, 1908.

Application filed September 26, 1906. Serial No. 336,334.

To all whom it may concern:

Be it known that I, EDWARD A. SANDERS, a citizen of the United States, residing in Oakland, in the county of Alameda and 5 State of California, have invented new and useful Improvements in Sheet-Metal Window Construction, of which the following is a specification.

This invention relates to improvements 10 made in sheet-metal window-frame and sash, and is applicable more particularly to window-construction wherein the sashes are arranged, or adapted to swing as well as to slide in the frame.

15 The invention has for its object the production of a sheet-metal window-frame having several improved features and several important advantages over other constructions, especially with regard to the few parts 20 or members, and the cheapness and facility with which the same can be made from sheet metal and put together.

A further object is the production of a window-frame in which the sashes are readily 25 hung or arranged so as to swing on pivots, or to slide up and down, according as it may be desired to raise or lower the sash perpendicularly or to swing in the frame.

To such ends and objects chiefly, the invention 30 comprises certain novel construction and combination of sheet metal parts or members producing a sheet-metal window-frame and casing having separate runways for the upper and lower sashes, slideable shoes 35 carrying the sashes, and means pivotally attaching the sashes to the shoes, all as herein-after more fully described and pointed out in the claims at the end of the specification.

In the accompanying drawings which illustrate 40 the application of the said improvements to the construction of a frame with swinging and sliding sashes, of a sheet-metal window.

Figure 1 represents in front elevation a 45 window construction embodying the said improvements, with upper and lower sashes pivotally hung to swing horizontally, and also adapted to slide up and down, the window-casing being partly broken away at one 50 side to disclose the parts within. Fig. 2 is a transverse sectional-view vertically through the frame, and the upper and lower sashes. Fig. 3 is a sectional-view on an enlarged scale 55 of a portion of the frame or casing at one side and the vertical member of the sash adjacent to the casing at that side; the section being

taken horizontally through the upright members of the casing and sash. Fig. 4 is a similar horizontal section, taken through the frame and the upper sash at about the line 60 $x-y$ Figs. 1-2, but on an enlarged scale. Fig. 5 is a detail view, in perspective, of parts composing the frame, the shoe and the upright member of the sash which is attached to and carried by the shoe on that side. 65 Fig. 6 is a detail partly in section of one of the hinges or pivots on which the sash is hung in the frame.

In the several figures of the drawings the various parts or members are designated as 70 the stationary frame a , the sliding-shoes $b-c$, the stiles or upright members m ; the rails or horizontal members n of the sashes; and the hinges $f-g$ on which the sashes are hung.

With the view of reducing the number of 75 parts and the labor necessarily involved in fastening the parts together, the front-plate a' in which are formed the channels or runways for the upper and lower sashes, $D-E$, and the outer and inner vertical sides of the 80 stationary casing are made in one piece, united at the back by the back-plate 5. But where it may be necessary or more convenient to use smaller sheets of metal, the front and the sides can readily be formed of separate plates joined together by interlocking 85 their edges in the same manner as the back plate is secured to the sides 4.

The frame to carry an upper and a lower sash will thus be formed with two runways 90 extending from top to bottom, on both sides of the frame. But where a single swinging and sliding sash is employed, there will obviously be but one runway required on each side, and the frame can be formed accordingly. 95

Following the construction of similar swinging and sliding windows, each sash is hinged or pivoted to sliding bars or members usually termed the shoes; the same being a bar or strip fitted to slide easily up and down 100 in the runway between the stops of the frame and carrying the sash, which is hinged or pivoted to the shoe at each side. Springs p of some kind are interposed between the shoe, and the frame, or between the stile or side- 105 bar of the sash and the shoe for the purpose of holding the sash in place and producing a tight-joint between the shoe and the sash.

In my present improvements each shoe is formed of sheet-metal and preferably of a 110 single strip or piece, by bending a strip of metal of the required length and width into

the shape seen in Figs. 3, 4 and 5; the sides 6 being bent back parallel with each other, and the front face 7 made of curved shape in cross-section, corresponding to the curvature of the stile *m* of the sash.

5 Narrow grooves or recesses 8 in the channel to receive and confine the sides 6 of the shoe are formed by fastening against the back or bottom wall of the channel a strip 10 having 10 standing sides 12 at right angles to or parallel with the sides of the channel. This strip is riveted to the back of the channel, and is of less width than the channel, so as to leave a narrow space between each standing-side 9 15 and the adjacent side of the channel to receive the shoe. The recesses before mentioned are of proper depth to retain the shoe in place against lateral play, and of proper width to confine the shoe in the vertical 20 or sliding movement. This construction affords a simple and efficient means of confining and guiding the shoe in the frame.

The sash represented in the drawings in connection with the above described construction of metal frame and shoe contains 25 several novel features which are reserved for a separate application. The same are well adapted, however, to be used in connection with the present invention in the production 30 of a fire-proof swinging and sliding window, especially with regard to the feature of securing a close weather tight-joint at the sides between the shoes and the stiles of the sash, and to the feature of placing the pivots on 35 the outside where they are readily accessible without taking the frame apart or removing the sashes.

A detailed description of the manner of constructing the metal sash and of hanging 40 it in the frame is omitted in this specification, as the novel features thereof are not included in the present invention, which is not necessarily confined or restricted to the use of the particular construction of metal sash herein 45 shown.

The pivots *f*—*g* at the sides of the sash are provided with knuckles 14 secured to the outside of each upright bar, and are fastened to blocks 15, fixed on the shoes, so that the 50 pinties 16 are located on the outside where they are easily reached, instead of being on the inside of the frame. This arrangement has the further advantage of removing the pivots and their bearings from the inside of 55 the shoes out of the way of the springs *p*, and of reducing the dimensions in depth of the shoe and the channel or run-way on the frame.

Having thus described my invention, what I claim as new and desire to secure by Letters 60 Patent is:—

a metallic-window, a frame having a

front-plate provided with a channel with standing sides, a slideable shoe formed of sheet metal and fitted to slide between the standing-sides of the channel, a stationary 65 strip of less width than the channel secured to the back thereof and having sides standing parallel with the sides of the channel, said strip being adapted in connection with the sides of the channel to confine and guide the 70 shoe.

2. In a metallic-window, a frame having a front-plate provided with one or more channels with standing - sides formed integral therewith and with the sides of the frame, a 75 guide-strip in the channel and of less width than the channel and having side members standing parallel with the side-walls of the channel, and a shoe having side-members fitted to slide in the grooves between the said 80 strip and the sides of the channel, in combination with a sash fitted to the front face of the shoe and pivotally attached to the shoe, and springs interposed between the shoe and the back of the channel and attached to the shoe.

3. In a metallic-window, a frame comprising a front-plate having a channel or runway for each sash, the standing-sides of the channel being integral with the front-plate and 90 with the sides of the frame, in combination with a sash carrying shoe, adapted to slide longitudinally in the channel and having limited lateral play therein, said shoes having a front face and side-pieces standing at 95 right angles thereto and having a sliding fit between the sides of the channel, a stationary strip secured to the back of the channel and having forwardly extending members adapted to confine and guide the sides of the 100 shoe, springs interposed between the shoe and the back of the channel, and bearings for the sash-pivots located on the outside of the sash-stile and the shoes and connecting the sash thereto.

4. In a metallic-window, a frame formed with a guideway, a strip secured in said guideway having its opposite ends bent outward parallel to the sides of the guideway and located to form grooves between them, 110 in combination with a sash provided with a shoe of substantially U-shape, the outer or face ends of the shoe being arranged to slide in said grooves.

In testimony whereof I have signed my 115 name to this specification in the presence of two subscribing witnesses.

EDWARD A. SANDERS.
